UNITED STATES PATENT OFFICE

107,365

DESIGN FOR A TEXTILE FABRIC

John W. Snowden, Philadelphia, Pa.

Application November 13, 1937, Serial No. 72,833

Term of patent 3½ years

To all whom it may concern:

Be it known that I, John W. Snowden, a citizen of the United States of America, residing in Philadelphia, State of Pennsylvania, have invented a new, original, and ornamental Design for a Textile Fabric, of which the following is a specification, reference being had to the accompanying drawing, forming part thereof, wherein, the figure is a plan view of a piece of textile fabric showing my new design.

I claim:

The ornamental design for a textile fabric substantially as shown.

JOHN W. SNOWDEN.
